UNITED STATES PATENT OFFICE.

WILLIAM J. PATTERSON, OF SPRINGDALE, PENNSYLVANIA, AND ALBRECHT B. NEUMANN, OF CHICAGO, ILLINOIS.

CASTING PLANT.

No. 912,406.

Specification of Letters Patent.

Patented Feb. 16, 1909.

Application filed January 17, 1908. Serial No. 411,297.

To all whom it may concern:

Be it known that we, WILLIAM J. PATTERSON, a resident of Springdale, in the county of Allegheny and State of Pennsylvania, 5 and ALBRECHT B. NEUMANN, a resident of Chicago, in the county of Cook and State of Illinois, have invented a new and useful Improvement in Casting Plants; and we do hereby declare the following to be a full, 10 clear, and exact description thereof.

Our invention relates to a casting plant.

Our invention is more especially applicable to a pig metal casting plant in which the molten metal as it is brought from the blast 15 furnace in ladles is poured into an endless chain of molds at one end of said chain and the metal is solidified in said molds, so that when the molds arrive at the outer end of the chain the pigs are in condition to drop 20 from the molds as the molds are overturned and drop into a car stationed at that end of the chain to receive the same. In such form of casting apparatus it is very desirable to arrange for the pouring of the metal 25 from the ladles into the pouring basin so that there will be very little drop in the metal from the ladle to said basin, thereby preventing the splashing of the molten metal. It is also very desirable to have the 30 tracks upon which the ladle cars travel as well as the tracks on which the cars travel that receive the molded pigs all on the same level, which greatly simplifies the construction of the plant and facilitates the shifting of the cars in bringing them up into proper position in the casting plant as well 35 as in hauling them away.

The main objects of our invention therefore are to provide for the supporting of 40 the ladles in such position that when tilted the pouring spouts will be in close proximity to the reservoir or runner from which the molds are supplied, and to provide for the arrangements of the tracks on the same 45 level for the purposes above set forth.

To these ends our invention comprises the novel features hereinafter set forth and claimed.

Referring to the drawings Figure 1 is a 50 side elevation of our improved casting plant; Fig. 2 is an enlarged side elevation of a portion thereof; Fig. 3 is a plan view; and Fig. 4 is an enlarged end view of the support and cradle.

55 In the drawings the numeral 2 designates

the frame work of a suitable casting house, on the floor 3 of which are arranged the tracks 4 upon which the ladle cars 5 are adapted to travel. These cars 5 carry the ordinary ladles 6 which are removable therefrom 60 said ladles being provided with the main trunnions 7 and the supplemental trunnions 8.

A frame work 9 is erected to support the pig metal casting apparatus which comprises the sprockets 10 and 11 around which passes the endless chain or mold carrier 12. The molds are secured to this endless carrier 12 and as such a carrier together with the molds are so well known it has not been 65 deemed necessary to illustrate the same in detail. At the upper or outer end of the frame 9 is the chute 13 which delivers the pigs as they are discharged from the molds into the car 14 traveling on the track 15, 70 which is on the same level, or substantially the same level, as the tracks 4 upon which the ladle cars 5 travel.

Adjacent to the inner end of the mold carrier 12 is the stand or support 16 adapted 75 to support the cradle or swinging frame 17. This cradle 17 has the trunnions 18 which engage the bearings 19 in the stand 16, whereby said cradle is adapted to swing from said trunnions. The lower end of the 80 cradle 17 rests upon the stool 20. The lower end of the cradle is provided with the ring 21. Recesses 22 are formed in the cradle 17, 85 said recesses being provided with the inclined faces 23. A stop 24 is provided to 90 control the inward movement of the lower end of the ladle when seated within the cradle, as fully hereinafter set forth.

Located adjacent to the stand or support 16 is the basin 25 into which the molten 95 metal is poured from the ladle, said basin having the outlets 26 at each side thereof through which the molten metal flows into the molds of the mold carrier. It is usual to arrange two parallel chains of molds so 100 that the basin 25 is arranged between them in such a manner that the metal will flow from the openings 26 to each side thereof to supply the molds of the mold carriers.

Erected upon the platform 27 is the jib 105 crane 28 adapted to swing in the ordinary manner. At the outer end of the jib 29 is the pulley 30, and at the lower end of said jib on the main mast of the crane is the pulley 31. At the top of the main mast of 110

the crane is the pulley 32. The main mast of the crane is further provided with the pulley 33.

Located within suitable distance of the crane is the motor 34. A gear 35 on the motor shaft meshes with the gear wheel 36 on the counter-shaft 37. A gear wheel 38 on the shaft meshes with the gear wheel 39 on the worm shaft 40. This worm shaft 40 meshes with the worm wheel 41 on the shaft 42. On this shaft 42 is the drum 43. A second drum 44 has the clutch 45 provided for throwing said drum into and out of engagement with the shaft 42. Diagonally arranged pulleys 46 are arranged above the drum 44 in suitable bearings. A pulley 47 is arranged in line with the pulley 32 overhead and above the drum 43.

A chain 48 is connected to the block pulley 49 around which passes the cable 50, said cable passing over the pulley 30, thence down and around the pulley 31 and up and over the pulley 32, thence across to the pulley 47 and downwardly and around the drum 43. It is apparent that by winding or unwinding the cable on the drum 43 the chain 48 is raised and lowered, as fully hereinafter set forth. The rope or cable 51 for swinging the crane passes around the pulley 33 and thence over the pulley 46 and downwardly and around the drum 44.

The shaft 42 may be provided with the brake wheel 52 fitted with a suitable brake band 53 of ordinary construction, whereby the speed of the shaft 42 may be properly controlled.

A suitable traveling crane 55 is arranged to travel upon suitable supports 56 within the casting house, said crane being provided with the ordinary main trolley 57 and an auxiliary trolley or hoist 58. The main trolley is provided at its lower end with the hook 59, while the auxiliary trolley 58 is provided with the hook 60.

Arranged at one side of the casting house are the ladle supports 61 which are adapted to support the ladles 6 when said ladles are deposited thereon for the purpose of removing the scale, as fully hereinafter set forth.

When the plant is in operation the ladle cars 5 convey the molten metal in the ladles 6 from the blast furnaces along the tracks 4. The main trolley of the overhead crane is brought into position with its hooks 59 engaging the central trunnions 7 of the ladle, whereupon the ladle is lifted from the car 5 and deposited in the cradle 17. The supplemental trunnions 8 fit within the recess 22 of the cradle and the inclined faces 23 insure the guiding of the ladles into position properly within the cradle. When the ladle has been deposited in the cradle in this manner the hooks 59 of the main trolley 57 are released from the central trunnions 7 and the trolley withdraws

to one side, whereupon the swinging crane 28 which has been swung out of position is operated to bring its jib around in position for the chain 48 to be secured by the hook thereon to the ring 21 of the cradle 17. In order to swing the crane around in this position power is applied through the motor to drive the drum 43 which is thrown into engagement with the shaft 42 by the clutch 45. By the winding of the cable 51 on the drum 44 the crane is swung around into the position shown in Fig. 1. The clutch 45 is then thrown out of engagement with the drum 44 and the drum 43 is then brought into engagement with said shaft, whereupon the cable 50 is lowered to bring the chain 48 down into position to engage the ring 21 of the cradle 17. Power is then applied to rotate the drum 42 in the opposite direction, whereupon the cable 50 is wound on said drum so as to lift the chain 48 and with it the cradle 17. The cradle 17 being trunnioned in the stand 16, the ladle supported by said cradle is lifted and tilted in the manner indicated in Fig. 1 so as to pour the metal therefrom into the receptacle or reservoir 25. The pouring spout of the ladle is in very close proximity to the reservoir so that as the ladle is tilted gradually the metal flows from the ladle into the reservoir without splashing. The pouring continues by the gradual tilting of the cradle until all the metal has been poured from the ladle into the reservoir 25. The metal passes from the reservoir 25 through the openings 26 into the molds and is conveyed to the outer end of the conveyer where the pigs which have been solidified, are discharged by the chute 13 into the car 14. When, as stated, the metal has been poured from the ladle the drum 43 is so operated as to lower the chain 48 into position to bring the cradle again into the position indicated in Fig. 1, whereupon the chain 48 is released and the crane 28 swung out of the way. The main trolley 57 is then brought into position to have its hooks 59 engage the central trunnions 7 of the ladle whereupon said ladle is lifted from the cradle 17 and carried over to the support 61, whereupon the auxiliary trolley 58 is brought over in position to have its hook 60 engage the ring 62 in the bottom of the ladle. By operating the cables of the auxiliary trolley in the proper manner the ladle is brought into a horizontal position, whereupon the ladle is lowered onto the support 61. The ladle is then in position to have the scale removed therefrom. After the scale has been removed from the ladle it is again lifted by the crane 56 and deposited on one of the cars to be taken back to the furnace to receive a fresh charge of molten metal. In this manner the ladles are poured and lifted and carried in position to be de-

posed on the support 61 for sculling, the whole operation being done with great ease and without confusion. The arrangement makes it possible to handle the ladles with greater speed, and as a consequence the tonnage of the plant is greatly increased. By having the tracks for the ladle cars as well as the tracks for the pig metal cars on substantially the same level the shifting may 10 all be done on the same level while the necessity of running the ladle cars in on tracks at a higher level is dispensed with.

What we claim is:

1. In a casting plant, the combination of 15 an endless traveling mold-carrier, tracks at opposite ends of said mold-carrier, ladle-cars traveling on the tracks at inner end of said carrier, cars to receive the molded metal on track at outer end of said mold- 20 carrier, said tracks being on the same or substantially on the same level, and means for lifting the ladles from said cars and pouring the metal into the molds of said mold-carrier.

2. In a casting plant, the combination of 25 an endless traveling mold-carrier, a pouring basin or reservoir at the inner end of said mold-carrier, a stand or support adjacent to said basin, a ladle on said stand with its 30 pouring lip at all times in close proximity to said basin, and means for tilting said ladle.

3. In a casting plant, the combination of 35 an endless traveling mold-carrier, a pouring basin or reservoir at the inner end of said mold-carrier, a tilting stand or support adjacent to said basin, a ladle on said stand with its pouring lip in close proximity to 40 said basin, and means for tilting said stand or support.

4. In a casting plant, the combination of 45 an endless traveling mold-carrier, a pouring basin or reservoir at the inner end of said mold-carrier, a stand or support adjacent to said basin, a cradle on said stand, a ladle on said cradle with its pouring lip in close proximity to 50 said basin, and means for tilting said cradle.

5. In a casting plant, the combination of 55 an endless traveling mold-carrier, a pouring basin or reservoir at the inner end of said mold-carrier, a tilting stand or support adjacent to said basin having recesses therein, a ladle having trunnions engaging said recesses, said ladle having its pouring lip at 60 all times in close proximity to said basin, and means for tilting said stand.

6. In a casting plant, the combination of 65 an endless traveling mold-carrier, a pouring basin or reservoir at the inner end of said mold-carrier, a tilting stand or support adjacent to said basin having recesses therein, said recesses having inclined faces leading thereto, a ladle having trunnions engaging said recesses, said ladle having its pouring 70 lip in close proximity to said basin, and means for tilting said stand.

7. In a casting plant, the combination of 75 an endless traveling mold-carrier, a pouring basin or reservoir at the inner end of said mold-carrier, a tilting stand or support adjacent to said basin, a ladle on said stand with its pouring lip in close proximity to said basin, a crane, and means for connecting said crane to said stand to tilt the same.

8. In a casting plant, the combination of 80 an endless traveling mold-carrier, a basin or reservoir at the inner end of said mold-carrier, a stand or support adjacent to said basin, a cradle on said stand hinged at the upper inner end thereof, a ladle on said 85 cradle with its pouring lip in close proximity to said basin, and means for lifting the outer end of said cradle.

In testimony whereof, we, the said WILLIAM J. PATTERSON and ALBRECHT B. NEUMANN have hereunto set our hands.

WILLIAM J. PATTERSON.
ALBRECHT B. NEUMANN.
